UNITED STATES PATENT OFFICE.

WILLARD G. FORKEY, OF CHICAGO, ILLINOIS.

BUILDING CONSTRUCTION.

Application filed January 14, 1926. Serial No. 81,279.

My invention relates to improvements in building constructions, and it consists in the combinations, constructions, and arrangements herein described and claimed.

5 In forming the ceilings and floors of buildings where concrete is employed, it has been the practice to suspend wires from the reinforcing members embedded in the concrete, these wires being secured to what 10 is commonly known as pencil rods. The rods in turn are then secured to a metal lath by wires, and to this lath the plaster is subsequently applied.

It is obvious that this construction prevents the pencil rods from being disposed 15 in parallel relation, unless great care is taken in disposing the supporting wires in proper position. A second disadvantage from this construction lies in the fact that 20 it takes considerable time to secure the wires to the reinforcing means and then to the pencil rods.

The principal object of the invention is to overcome these disadvantages and other 25 disadvantages hereinafter pointed out, and to this end I provide what I term "hangers" which may be partially embedded in the concrete, these hangers having novel means for supporting the pencil rods and for permitting 30 the pencil rods to be disposed substantially parallel with respect to each other, and be spaced apart any distance desired.

A further object of my invention is to provide a device of the type described 35 which cuts down the time in securing what is called the "furring" to the ceiling.

Other objects and advantages will appear in the following specification, and the novel features of the invention will be particularly pointed out in the appended claims.

40 My invention is illustrated in the accompanying drawings, forming part of this application, in which—

Figure 1 is a sectional view of a floor 45 showing my device operatively applied thereto,

Figure 2 is a side elevation of the novel type of hanger,

Figure 3 shows the method of securing 50 the hanger in place prior to its being embedded in the concrete, and

Figure 4 is a sectional view of a modified form of the device.

In carrying out my invention, I make use 55 of shoring 1 now employed in general building construction. This shoring extends

from the floor below and carries forms 2, the forms being split at 3 for receiving a portion of the hangers 4.

The hangers 4 form my invention, while 60 the shoring 1 and the forms 2 form no part of my invention except in so far as they cooperate with my invention. In Figure 2, I show the construction of the hangers 4. It will be noted from this figure that 65 the hanger 4 has large openings 5 for permitting the hanger to be embedded in the concrete 6 and the concrete to flow into the openings. The hanger is further provided with small openings 7, these openings being 70 preferably spaced five-eighths of an inch apart, and being of a size large enough to slidably receive pencil rods 8. At each end of the hanger, I provide an opening 9 through which a nail or other supporting 75 means 10, see Figure 3, may be disposed. The nail 10 is used for supporting the hanger on the forms 2 prior to the time that the cement is poured around the hanger.

The nails 10 prevent movement of the 80 hanger toward the forms 2, while staples 11 prevent movement of the hangers in the opposite direction. It will be also noted that the staples straddle the nails 10. This construction prevents the longitudinal movement 85 of the hangers. The hangers are supported in the position shown in Figure 3, and it will be noted that the openings 5 are positioned above the tops of the forms 2 where they will receive the concrete when 90 it is poured.

From the foregoing description of the various parts of the device, the operation 95 thereof may be readily understood. The shoring 1 and the forms 2 are first disposed in place when forming the floor and support pans 12. These pans are U-shaped, as shown in Figure 1, and the legs of the pans rest upon the upper surfaces of the forms 2, the legs of one set of pans being 100 spaced from the legs of the adjacent set for permitting concrete to fall down between the pans and rest upon the forms 2. Prior to the pouring of the cement, reinforcing members, not shown, may be 105 laid upon the tops of the pans. The concrete is now poured and partially embeds the hangers 4. The portions of the hangers having the row of openings 7 therein are exposed, and when the shoring and the forms are removed, these portions may carry 110 the pencil rods 8. The openings 7 are spaced

very close together. This permits one row of pencil rods consisting of a number of sections to be placed almost end to end, because the end of one section will be placed 5 in an opening and the end of the next succeeding section will be placed in an opening adjacent thereto. Moreover, this manner of suspension permits the pencil rods 8 to be disposed in substantially parallel 10 rows because the openings 7 are spaced so close together as to permit a single section of the pencil rods to be passed through substantially aligned openings in adjacent hangers 4. It is obvious that the openings 7 in 15 the hangers 4 take the place of the numerous wires which are now required to support the pencil rods.

After the pencil rods have been disposed in place, the metal lath 13 is wired, or otherwise 20 secured to the pencils rods. The device is extremely simple in construction, and provides a novel and efficient means for supporting the pencil rods in adjusted position without the necessity of supporting each 25 pencil rod separately by a wire.

In Figure 4 I show a slightly modified form of the device. It will be noted from this figure that the hangers 4 directly support the metal lath 13, the lath being 30 secured to the hangers by wires 50 that are threaded through the openings in the lath and through the openings 7. In this form of the device, the pencil rods 8 are done

away with. The type of lath employed in this form of the device is preferably 35 that known by "hy-rib" or "self-centering" lath.

I claim:

1. A device of the type described comprising forms for supporting concrete flooring while said flooring is hardening, hangers having a plurality of relatively large openings and a plurality of relatively small openings therein, means cooperating with said forms for holding said hangers while said flooring is hardening, said hangers being positioned so as to become embedded in the concrete flooring, and the relatively large openings being filled with concrete, and pencil rods removably disposed in the relatively small openings. 40

2. A device of the type described comprising forms for supporting concrete flooring while said flooring is hardening, hangers having a plurality of relatively large openings and a plurality of relatively small openings therein, means cooperating with said forms for holding said hangers while said flooring is hardening, said hangers being positioned so as to become embedded in the concrete flooring, and the relatively large openings being filled with concrete, pencil rods removably disposed in the relatively small openings, and metal lath secured to 45 50 55 said pencil rods. 60

WILLARD G. FORKEY.
